UNITED STATES PATENT OFFICE.

JOSEPHINE STORMO, OF GARRETSON, SOUTH DAKOTA.

INVALID'S SWING.

1,216,878.

Specification of Letters Patent. Patented Feb. 20, 1917.

Application filed April 29, 1916. Serial No. 94,304.

To all whom it may concern:

Be it known that I, JOSEPHINE STORMO, a citizen of the United States, residing at Garretson, in the county of Minnehaha and 5 State of South Dakota, have invented certain new and useful Improvements in Invalids' Swings; and I do hereby declare the following to be a full, clear, and exact description of the invention, such as will enable others skilled in the art to which it 10 appertains to make and use the same.

My invention relates to exercising swings for invalids; and, to this end, it consists of the novel devices and combinations of 15 devices hereinafter described and defined in the claims.

The object of the swing is to provide exercise for invalids who are unable to otherwise obtain the same, and particularly persons effected with infantile paralysis. 20

Referring to the drawing:

The single perspective view illustrates the invention.

The numeral 1 indicates a room diagrammatically illustrated, and having secured to the ceiling thereof, four hooks 2 in rectangular arrangement. A relatively large hoop or ring 3 is suspended in a horizontal position from the hooks 2 by four relatively 25 heavy coiled springs 4. Two pairs of cables 5 are secured at one of their ends to the hoop 3 at diametrically opposite points. The cables 5 of each pair are secured to the hoop 3 quite close together, and the lower 30 ends of said cables are secured to the four corners of a seat 6.

A large padded hoop or ring 7 surrounds the cables 5 and is suspended from the hoop 3 by a pair of cables 8. The upper ends of 40 the cables 8 are secured to the hoop 3, one between each pair of the cables 5, and their lower ends are secured to the hoop 7 at diametrically opposite points. The hoop at 7 is provided at 9 with additional padding to 45 afford a neck rest. Obviously, the cables 5 may be adjusted, in any suitable way, to support the seat 6 the required distance above the floor and, likewise, the cables 8 may be adjusted to properly position the 50 neck rest 9 with respect to the seat 6.

A person exercising in the swing sits on the seat 6 with the back of his neck resting on the neck rest 9 of the hoop 7, thus leaving

his whole body free for exercise, particularly his arms and legs. Ordinarily, a person, while exercising in the swing, will hold onto certain of the cables 8, but if he is strong enough, he can let go and support himself entirely by the engagement of his neck and head, thus leaving his arms free 55 for exercise.

From the above description, it is evident that the springs 4 yieldingly support the seat 6 and hook 7, thus making the swing very comfortable. The cables 5 and 8 will 60 permit independent, universal movements of the seat 6 and hoop 7 with respect to each other, while the person is exercising.

The above described swing has, in actual usage, proven highly efficient for the purpose had in view.

What I claim is:

1. An invalid's swing comprising independent cable supported seat and hoop-like neck rest, the cables for the seat extending 75 through the neck rest.

2. The combination with an overhead support, of a hoop, coiled springs suspending the hoop from the overhead support, a seat and a neck rest, and cables independently suspending the seat and neck rest 80 from the hoop.

3. The combination with an overhead support, of a hoop, coiled springs suspending the hoop from the overhead support, a seat, 85 cables suspending the seat from the hoop, and a neck rest suspended from the hoop.

4. The combination with an overhead support, of a hoop, coiled springs suspending the hoop from the overhead support, a seat, 90 cables suspending the seat from the hoop, a neck rest, and cables suspending the neck rest from the hoop.

5. The combination with an overhead support, of a hoop, coiled springs suspending 95 the hoop from the overhead support, a seat, cables suspending the seat from the hoop, a padded hoop affording a neck rest, and cables suspending the padded hoop from the first noted hoop.

In testimony whereof I affix my signature in presence of two witnesses.

JOSEPHINE STORMO.
